DESIGN FOR A DECK OF PLAYING CARDS

Michael J. White, Halifax, Nova Scotia, Canada

Application May 13, 1940, Serial No. 92,316

Term of patent 14 years

To all whom it may concern:

Be it known that I, Michael J. White, a subject of the King of Great Britain, residing at Halifax, in the Province of Nova Scotia and Dominion of Canada, have invented a new, original, and ornamental Design for a Deck of Playing Cards, of which the following is a specification, reference being had to the accompanying drawings, forming a part thereof.

The backs of the cards are conventional.

I claim:

The ornamental design for a deck of playing cards, as shown and described.

MICHAEL J. WHITE.
